CLAIM

The ornamental design for a cart, as shown and described.

DESCRIPTION

FIG. 1 is a perspective front left view of a cart showing our new design.

FIG. 2 is a perspective view of the front of the cart of FIG. 1.

FIG. 3 is a perspective front right view of the cart of FIG. 1.

FIG. 4 is a perspective right side view of the cart of FIG. 1.

FIG. 5 is a perspective back right view of the cart of FIG. 1.

FIG. 6 is a perspective view of the back of the cart of FIG. 1.

FIG. 7 is a perspective back left view of the cart of FIG. 1.

FIG. 8 is a perspective left side view of the cart of FIG. 1; and,

FIG. 9 is a perspective view of the top of the cart of FIG. 1. The broken lines shown in the figures are included for the purpose of illustrating portions of the cart and form no part of the claimed design.

1 Claim, 9 Drawing Sheets
